RELEASE DEVICE FOR WRINGERS

Walter L. Kauffman, II, Erie, Pa., assignor to
 Lovell Manufacturing Company, Erie, Pa., a
 corporation of Pennsylvania

Application March 17, 1937, Serial No. 131,334

7 Claims. (Cl. 68—263)

Power wringers are commonly provided with safety release mechanisms by which the pressure on the rolls may be instantly released. The present invention is designed to improve such release mechanisms. In carrying out the invention operating devices are provided which are arranged to be manually actuated to effect a release. This is accomplished by converting an inward movement of the operating member to an endwise movement which will trip the release device and providing in this way a very much simplified mechanism for effecting the release. The invention contemplates also an operating bar extending longitudinally of the wringer which is operative by an inward movement of the bar at either end, or the bar as a whole. Features and details of the invention will appear from the specification and claims.

A preferred embodiment of the invention is illustrated from the accompanying drawing as follows:

Fig. 1 shows a front elevation of the wringer, partly in section to better show construction.

Fig. 2 an enlarged section on the line 2—2 in Fig. 1.

Fig. 3 a section on the line 3—3 in Fig. 2, showing the latch parts in a position following release.

Fig. 4 a similar view with the parts assumed during the movement of the top bar to set position.

The wringer has a frame consisting of a base 1, and side stiles 2 and 3. A lower roll 4 and an upper roll 5 is provided, the lower roll having a shaft 6 journaled in bearings 7, the bearings 7 being arranged in the side stiles. The upper roll 5 has a shaft 8 which operates in bearings 9 slidably mounted in the side stiles. A spring 10 rests on the upper bearings and exerts pressure from the top bar 11 through an adjusting screw 12, the screw operating through a nut 13 in the top bar.

The top bar is detachable. One end is secured by interlocking shoulders formed by stabbings. The stabbing 14 on the side stile forming a shoulder 15, and a stabbing 16 on the end of the top bar forming a shoulder 17 engaging the shoulder 15. These shoulders are arranged to disengage when the opposite end of the top bar is swung upwardly in release so as to give more definite release movement to the top bar.

A release mechanism is provided for the opposite end of the top bar. A latch member 20 is provided with a slot 21 which has portions 22 and 23 extending each side of a pivot pin 24 when the latch member is in set position as shown in Figs.

1 and 3. These portions 22 and 23 are preferably inclined with the apex at the set position. The latch member is of channel form having the sides 20—a and connecting plate 20—b. Hooks 25 are formed on the sides 20—a and are adapted to enter notches 26 in the upper inner corners of the stile 2, the hooks engaging the shoulders formed by the upper end of the notch, the plates having cut-away portions 30 to clear the portion of the side stile above the notch.

The latch has a trip finger 27 which is adapted to engage the under-side of a cross member 28 forming a portion of the trip member. The cross member extends through slots 29 in the top and extends into operating bars 31—31 at the front and rear of the wringer. A companion cross member 28a extends through slots 29a, and is secured in the operating bars. The cross members 28 and 28a have cam surfaces 32 which are adapted to engage the ends of the slots 29 and 29a respectively when either cross member is moved inwardly, and through this engagement to move the trip cross plate 28 endwise sufficiently to release the finger 27 and permit the inner end of the latch to swing upwardly so as to release the hook 25 and consequently the top bar from the side stile. This release of the release end of the top bar as it swings up moves the shoulder 17 outwardly endwise so as to bring this shoulder beyond the alignment with shoulder 15 and thus effect the release of the resetting mechanism and this permits the further opening of the top bar to free the wringer rolls from pressure. A spring 33 is secured to the cross plate 28a and yieldingly draws the top member comprising the cross plates 28, 28a and the connecting operating members 31 toward the right or set position. The cross plate 28 has a lip 34 which forms an inclined surface on the upper part of the cross plate 28. A pin 35 extends through an opening 36 in the connecting plate 20b. This pin is provided with a head 37, and a spring 38 is tensioned between the head 37 and the connecting plate 20b, thus yieldingly pressing the inner end of the latch downwardly. As soon as the top moves upwardly and the hook has cleared the upper end of the stile the spring 38 presses down the inner end of the latch, and the finger 27 operating on the incline 34 crowds the latch toward the right (see Fig. 3) sufficiently to permit the finger to clear the cross plate 28. The portion 22 of the slot 21 permits the end movement for this clearance.

The downward movement of the inner end of the latch is obstructed by stop 39 riveted on the under-side of the cross plate 28. As soon as the 55

inner end of the latch reaches this stop the further pressure of the spring 38 pressing downwardly on the latch effects a movement of the latch toward the left by reason of the inclined or camming surfaces in the portion 22 of the pivot slot.

As the top is reset the bottom of the hook 25 engages the top of the stile. This under-side of the hook has a cam surface 25a which forces the latch toward the left so that the hook may clear the inner face of the stile. (See Fig. 4.) The portion 23 of the pivot slot permits this endwise movement. The hook is yieldingly carried into the notch 26 by the pressure of the spring 38 and the camming action of the portion of the slot 23 on the pin 24 thus bringing the parts to the position of engagement shown in Fig. 1, and as the pressure of the main spring is exerted on the top the pin 24 seeks the upper or apex of the slot retaining the engagement of the hook in the notch and also the position of the finger 27 under the trip plate 28.

It will be noted that an inward or outward movement of either operating member 31 forces the endwise release movement of the trip plate 28. If the operating members 31 are hit toward the ends only one of the cammed surfaces 32 may be brought into active operation so as to effect this endwise movement. In any event, the operation of operating bar 31 effects this endwise movement either through an inner movement of one or the other cross plates or by both of them. The endwise yielding of the latch member on trip plate 28 through the incline 34 may permit of the resetting of the finger relatively to the trip plate but in this case the spring 38 would have to be of such stiffness as to overcome the force of the spring 33 resisting the endwise movement of the trip plate 28.

40 The specific latching mechanism disclosed in this application forms the subject of a companion application executed on even date herewith Serial No. 131,333.

What I claim as new is:

45 1. In a wringer, the combination of a frame; rolls mounted in the frame; yielding means releasably supplying pressure to the rolls from the frame; and a release device for the means comprising a trip member effecting a release by an endwise movement thereof and including a plurality of connected and longitudinally spaced slides in the frame having cams moving the member endwise of the wringer with a movement of the slides crosswise of the wringer.

50 2. In a wringer, the combination of a frame; rolls mounted in the frame; yielding means releasably supplying pressure to the rolls from the frame; and a release device for the means comprising a trip member effecting a release by an endwise movement thereof and including a plurality of connected and longitudinally spaced slides in the frame having cams moving the member endwise of the wringer with a movement of either slide and both slides crosswise of the roll axes.

55 3. In a wringer, the combination of a frame;

rolls mounted in the frame; yielding means releasably supplying pressure to the rolls from the frame; and a release device for the means comprising a trip member effecting a release by an endwise movement thereof and including a plurality of longitudinally spaced slides in the frame having cams moving the member endwise of the wringer with a movement of the slides crosswise of the roll axes and an operating bar extending longitudinally of the wringer rigidly secured to 10 the slides.

4. In a wringer, the combination of a frame; rolls mounted in the frame; yielding means releasably supplying pressure to the rolls from the frame; and a release device for the means comprising a trip member effecting a release by an endwise movement thereof and including a plurality of longitudinally spaced slides extending to the front and rear of the frame and having cams moving the member endwise of the wringer 15 with a movement of the slides crosswise of the plane of the roll axes in either direction and operating bars rigidly connected to the slides at both the front and rear of the wringer.

5. In a wringer, the combination of a wringer frame; rolls mounted in the frame; a releasable top on the frame; a pressure means exerting pressure from the top to the rolls; and a release device for releasing pressure on the rolls releasably securing the top bar on the frame and comprising an unstable latch between the top bar and the frame, a trip member locking the latch in set position, said trip member releasing the latch by a movement of the trip member endwise of the wringer, said trip member including an operating bar, and mechanism converting a movement of the bar crosswise of the wringer to an endwise movement of the member.

6. In a wringer, the combination of a wringer frame; rolls mounted in the frame; a releasable top on the frame; a pressure means exerting pressure from the top to the rolls; and a release device for releasing pressure on the rolls and releasably securing the top bar on the frame and comprising an unstable latch between the top bar and the frame, a trip member locking the latch in set position, said trip member releasing the latch by a movement of the trip member endwise of the wringer, said trip member including an operating bar and mechanism converting a movement of any part of the bar crosswise of the wringer to a movement of the member endwise of the wringer.

7. In a wringer, the combination of a wringer frame; rolls mounted in the frame; a releasable top on the frame; a pressure means exerting pressure from the top to the rolls; a release device for the means comprising a trip member effecting a release by a movement thereof endwise of the wringer and including a plurality of longitudinally spaced slides mounted in the top having cams moving the member endwise of the wringer with a movement of the slide crosswise of the wringer.

WALTER L. KAUFFMAN, II. 65
